UNITED STATES PATENT OFFICE

2,346,479

LEVELING ROD AND RANGE POLE

Harry W. Fatkin, Westville, N. J., assignor to
 Warren-Knight Company, Philadelphia, Pa., a
 corporation of Pennsylvania

Application June 15, 1943, Serial No. 490,857

4 Claims. (Cl. 33—74)

This invention relates to leveling rods and range poles, that is to say apparatus adapted to be used by surveyors and the like in connection with surveying instruments for the purposes for which leveling rods and range poles are usually employed.

The principal object of the present invention is to provide apparatus which will combine the usefulness of a leveling rod and a range pole, and which may be readily dismantled into compact form for transportation.

A further object of the invention is to provide an apparatus of the character aforesaid by means of which the operations of the surveyor will be considerably simplified, and that the readings and notes necessary in connection therewith will be more direct.

A further object of the invention is to provide apparatus of the character aforesaid which may be carried in a dismantled condition, but which may be readily and expeditiously set up at the place where it is desired to use the same.

A further object of the invention is to provide, as a portion of the apparatus, an improved form of range pole in which the coloring will be permanent in character, and which is so constructed and arranged that the same may be readily dismantled, and which may be assembled in various lengths and arrangements as may be required.

The nature and characteristic features of the invention will be more readily understood from the following description, taken in connection with the accompanying drawings forming part hereof, in which:

Figure 1 is a front elevation of apparatus of my present invention in its assembled or set up condition ready for use;

Fig. 2 is a side elevation thereof;

Fig. 3 is a side elevation, partly in section, of a portion of the apparatus shown in Figs. 1 and 2, the same being shown in the condition in which the parts are brought together for carrying the same when they are dismantled from the pole or rod on which they are mounted for use.

Fig. 4 is a rear elevation of the portion of the apparatus shown in Fig. 3;

Fig. 5 is a top or plan view thereof;

Fig. 6 is a side elevation of one of the sections of a breakdown pole or rod upon which the apparatus shown in Figs. 3 to 5 is adapted to be mounted as illustrated in Figs. 1 and 2 of the drawings;

Fig. 7 is a view similar to Fig. 6 showing another section of the pole of a contrasting color;

Fig. 8 is a view similar to Fig. 6 illustrating a form of the lowermost section of the pole or rod,

adaptable for use in certain conditions, as for example when the assembled rod is used principally as a range pole; and

Fig. 9 is a similar view of a modified form of pointed section for use at the lower end of the pole or rod.

It should, of course, be understood that the description and drawings herein are illustrative merely, and that various changes and modifications may be made in the structure disclosed without departing from the spirit of the invention.

Referring to the drawings, the rod or pole is preferably made of a plurality of sections, each of a uniform length, as for example, one foot. Preferably, there will be provided an equal number of such sections 10, of one color, usually white, and an equal number of such sections 11, of a contrasting color, say red.

Each of said sections is provided at one end with a central recess 12 internally threaded, and at the other end with a complementally threaded teat 13, the arrangement being such that the threaded teat 13 of any section may be threaded into the recess 12 at the end of another section and the pole thus assembled. The several sections 10 and 11 of the pole are preferably made of one of the modern plastic materials so that the color will be permanent, and no repainting of the pole or rod will be necessary as is now required from time to time with the range poles at present in common use.

It will also be seen that any desired number of sections, within practical limits, may be used and the pole thereby lengthened or shortened as may suit the purposes of the user.

The several sections of the pole may be made solid, and the threaded recess and teat at the respective ends of each section may be molded as integral parts thereof. However, if preferred, the sections may be made hollow with inserted threaded portions at the ends.

When it is desired to use the rod or pole primarily as a range pole, the lowermost section may be made as shown in Fig. 8 of the drawings, that is to say, instead of the threaded teat 13, the lower end of said section 14 may be provided with a recess 15, internally threaded, and into which threaded recess 15 there may be mounted a complementally threaded point member 16, which may be made of hardened steel, or if desired the same may also be made of plastic material, but in any event the point member 16 is readily renewable when worn or damaged.

Also, if desired, the lowermost section of the

pole or rod may be made as illustrated in Fig. 9 in which said lowermost section 17 is provided with an integrally formed pointed portion 18.

The measuring attachment adapted to be used in connection with the pole or rod is shown in Figs. 3, 4 and 5 of the drawings, with the parts in the relative positions assumed when said attachment is removed from the pole or rod for carrying. The several parts of the measuring attachment are shown in operative positions on the pole or rod in Figs. 1 and 2 of the drawings. This attachment comprises three portions, to wit, an upper portion A, an intermediate portion B, and a lower portion C.

The intermediate portion B of the measuring attachment comprises a sleeve 20, which is adapted to be mounted on the assembled pole or rod hereinbefore described and to be clamped thereto at desired locations by means of the thumb screw 21. The sleeve 20 is provided on its front portion with lugs 22, which support a plate 23 to which the central portion of a tape 24 is secured, by screws 27, or any other preferred means.

The rear portion of the sleeve 20 is also provided with a longitudinally extending lug 25 which serves as a seat for the support of a bar member 26 which is secured thereto and which will be hereinafter further referred to.

The upper and lower portions A and C respectively of the measuring attachment are substantially alike. Each of said portions comprises a sleeve 30, mounted in alinement with the sleeve 20 of the portion A. The sleeve 30 is also provided with a thumb screw 31, which serves to secure sleeve 30 at any desired position on the range pole.

On the front side of the sleeve 30 there is also provided a lug 32 which serves to support a housing 33. Within the housing 33 there is rotatably mounted a drum 34 upon which the tape 24 is adapted to be wound, and to be unwound therefrom. Preferably the drum 34 is normally under the tension of a coiled leaf spring 35 which permits the unwinding of the tape 24 from the drum 34 when the portions A and C of the measuring attachment are mounted at the respective ends of the pole as shown in Figs. 1 and 2 of the drawings, and also serving normally to keep the tape 24 under a proper degree of tension when the parts A and C are in their separated operative positions.

The bar member 26, which is secured to the sleeve 20 of the portion B, is provided at each end with an extension 36 having an open ended slot 37 through which the shank of the thumb screw 31 extends, the arrangement being such that when the measuring attachment is mounted on the pole or rod, and the thumb screws 31 are loosened, the sleeves 30 of portions A and C may be moved away from the sleeve 20 of portion B, but when the parts are in the position shown in Figs. 3 and 4, the bar member 26 will serve to maintain the sleeves 30 of portions A and C, and the sleeve 20 of the portion B, in alinement with each other to facilitate the mounting of the measuring attachment on the pole or rod.

It will be noted that the thumb screws 31 are somewhat shorter than the thumb screw 21, and thereby permit the clamping of the sleeves 30 of the portions A and C to the slotted end portions of the bar member 26 as shown in Figs. 3 and 4 of the drawings, yet permitting the sleeves 30 of the portions A and C to be clamped at extended locations on the pole or rod as shown in Figs. 1 and 2 of the drawings.

The tape 24 is preferably made of a strip of steel or other relatively non-stretchable material and graduated on one face in any desired manner. Preferably the graduations would start at 5 0 in the center of the tape, and marked in each direction from said center, thus permitting direct reading of "cut and fill" from the instrument.

It will be readily seen that the pole or rod may be made of any desired length, within practical 10 limits, and in the use of the same the intermediate portion B of the measuring attachment may be raised or lowered on the rod and secured thereon at any desired location, thus greatly facilitating the taking of the measurements in the running of a level line.

When the apparatus is in the collapsed condition for carrying the same, and it is desired to use the same, the several sections of the rod or pole are first joined to each other, usually with the differently colored sections alternately disposed, the sections being joined by threading the teat 13 of one section into the recess 12 of another section.

The measuring attachment as illustrated in Figs. 3, 4 and 5 may then be slid on the rod and the thumb screws 31, which secure the sleeves 30 of the end portions A and C to the bar member 26, are loosened and the end sections A and C are then moved on the rod to the desired locations, usually near the respective ends of the rod, and then secured in such locations by tightening the thumb screws 31.

It will be seen that, by the use of the foregoing apparatus, the surveyor's operations in running levels will be greatly facilitated, and the apparatus may be readily carried from place to place notwithstanding that rods of more than ordinary length may be employed. Furthermore the rod may be used as a range pole without the measuring attachment, and said rod will be of a more durable and lasting character than the poles at present in common use.

I claim:

1. Apparatus for use by surveyors and the like comprising a rod or pole, and a measuring attachment mounted thereon, said measuring attachment including a measuring tape and comprising three separable portions each slidably mounted on the rod, means for clamping said portions at desired locations on the rod, the intermediate portion having means for securing the central part of the measuring tape, and each end portion having a housing in which one end of said tape is wound, the intermediate portion having a member to which the end portions are clamped when the measuring attachment is removed from the rod.

2. Apparatus for use by surveyors and the like comprising a rod or pole, and a measuring attachment mounted thereon, said measuring attachment including a measuring tape and comprising three separable portions each including a sleeve for slidably mounting the same on the rod, means in each of said sleeves for clamping the same to the rod, the intermediate portion having means for securing the central part of the measuring tape, and each end portion having a housing in which one end of said tape is wound, the intermediate portion having a bar member secured thereto, said bar member having extending end portions to which the end portions of the measuring attachment are adapted to be clamped when the measuring attachment is removed from the rod.

3. Apparatus for use by surveyors and the like

comprising a rod or pole, and a measuring attachment mounted thereon, said measuring attachment including a measuring tape and comprising three separable portions each including a sleeve for slidably mounting the same on the rod, a clamping screw mounted in each of said sleeves, the intermediate portion having means for securing the central part of the measuring tape, and each end portion having a housing in which one end of said tape is wound, the intermediate portion having a bar member secured thereto, said bar member having extending end portions each having an open ended slot adapted to receive the shank of the clamping screw of one of the end portions of the measuring attachment thereby to permit the end portions to be clamped to the bar member when the measuring attachment is removed from the rod.

4. Apparatus for use by surveyors and the like comprising a rod or pole made of separable sections, and a measuring attachment mounted

thereon, said measuring attachment including a measuring tape and comprising three separable portions each including a sleeve for slidably mounting the same on predetermined sections of the rod, a clamping screw mounted in each of said sleeves, the intermediate portion having means for securing the central part of the measuring tape, and each end portion having a housing in which one end of said tape is wound, tension members in said housing connected to said tape, the intermediate portion having a bar member secured thereto, said bar member having extending end portions each having an open ended slot adapted to receive the shank of the clamping screw of one of the end portions of the measuring attachment thereby to permit the end portions to be clamped to the bar member when the measuring attachment is removed from the rod.

20

HARRY W. FATKIN.
